MELLISSA E. BULKLEY, OF PROVIDENCE, RHODE ISLAND.

Letters Patent No. 65,168, dated May 28, 1867.

IMPROVEMENT IN CORSET-CLASPS.

The Schedule referred to in these Letters Patent and making part of the same.

TO ALL WHOM IT MAY CONCERN:

Be it known that I, MELLISSA E. BULKLEY, of the city and county of Providence, and State of Rhode Island, have invented a new and useful Improvement in Corset-Clasps; and I do hereby declare that the following is a full and exact description of the same, reference being had to the accompanying drawings, making part of this specification, in which—

Figure 1 is a view of a pair of ordinary corset-steels or springs and clasps to which my said improvement is applied.

Figure 2 is another view edgewise of one of said springs and said improvement.

These springs are of metal, and are enclosed by sewing into the edges of the garment from which the clasps *a a a* protrude, whereby the two edges are easily and quickly united or unclasped to put the garment on or off, the springs answering the purpose of the old-fashioned "busk" to give shape to the garment and support to the wearer thereof. It will be observed, however, that eye-piece *n* of the clasp, when placed upon the stud or pin *i*, bears upon the part of the fabric which covers the spring to which the stud is secured, and it is found in practice that the fabric is soon worn away by the clasp, and, in consequence, the garment becomes soiled and even ragged long before any other portion is defaced, and my improvement has for its object the remedying of this difficulty by preventing this wear altogether. My invention consists in using a shield, *s*, of metal, or other suitable material, on the stud *i*, between the clasp-eye *n* and the fabric which covers the spring to which the studs are secured, so that the eye *n* will bear and wear upon the shield instead of the fabric.

To accomplish this the cloth may be punctured to admit the shanks of the three studs, and then the shield is placed on the stud, after which the shank is put through the puncture in the fabric and inserted in the perforation in the spring and riveted on the other side, when the spring may be enclosed by sewing it into the edge of the fabric; or the stud, with the shield thereon, may be riveted to the spring, as shown in the drawings, and a slit cut at the proper places to press the stud and shield through, and afterwards sewing the fabric over the spring. The shield need be only a trifle larger in diameter than the head of the stud to answer all purposes.

I would also state that, in lieu of the shield of metal, I intend to use shields of leather, hard rubber, bone, ivory, etc., either of which materials will answer the purpose. I have also successfully used an eyelet of the ordinary kind, inserted in the fabric where the stud passed through, which answers the purpose of and is in all respects the equivalent of the shield, but I prefer the shield constructed in the form of a disk or washer on the shank of the stud, as better adapted for the purpose.

What I claim, and desire to secure by Letters Patent, is

The use of the shield *s*, or its equivalent, in combination with the clasp, constructed substantially as described for the purpose specified.

MELLISSA E. BULKLEY.
